UNITED STATES PATENT OFFICE

EVAN GEORGE WILSON, OF BLUNDELLSANDS, NEAR LIVERPOOL, ENGLAND

DEVICE FOR USE IN STRETCHING SKINS OR THE LIKE

Application filed February 23, 1929, Serial No. 342,268, and in Great Britain February 29, 1928.

This invention relates to the straining or stretching—usually with the object of drying—of skins, hides, pelts, or the like, (hereinafter, for convenience of reference, designated “skins”) on perforate surfaces (hereinafter, for convenience of reference, designated “frames”) by the aid of devices or appliances whereto portions of the edge of a skin may be detachably held or gripped, and which may be anchored in selected or appropriate mesh or other openings or interstices of the frame.

My invention is characterized by the inclusion, in an appliance of the type before referred to, of a plurality of hook-like members or protuberances or stops suitably spaced apart and arranged or disposed one behind another for the purpose hereinafter described.

The skin-holding or gripping means may embody a jaw adapted to receive a portion of the edge of a skin, and comprising relatively fixed and movable components or members, the movable component consisting of a cam or wedge the operative face of which is transversely grooved or ridged or otherwise provided with suitable relative projections and depressions, and said cam or wedge constituting an arm of a lever the other arm whereof forms a thumb piece whereby said cam or wedge may be moved by hand.

Preferably, there is included a spring or springs which tend to maintain said cam or wedge in its operative or skin-engaging position.

The relatively fixed jaw component preferably projects forwardly somewhat beyond the movable jaw component, in order that it may act as a guide to the operator, assist the leading of a portion of the edge of a skin into the jaw gap, and maintain a skin out of contact with the meshes or interstices of the frame.

Said hook-like members or protuberances or stops may be connected to a plate, or the like, which is removably associated with the body of the appliance.

According to another modification, the appliance is divided or separated into two portions which are so formed and connected or

articulated together that the appliance—as a whole—may be readily shortened at will, in order that additional or supplementary tension may be imposed on a skin when in situ on the frame.

I will further describe my invention with the aid of the accompanying sheet of explanatory drawings, which illustrate, by way of examples only, several modes of carrying the invention into effect.

In said drawings:—

Fig. 1 is an elevation, and Fig. 2 a plan view of a skin-holding or gripping appliance, according to one construction.

Fig. 3 is an inverted plan view of a fragment of the appliance.

Fig. 4 is an inverted plan view of a fragment of an appliance of modified construction.

Fig. 5 is a perspective view illustrating a part of a skin stretched on and detachably secured to a portion of a frame by the aid of the appliances.

Fig. 6 is a side elevation, drawn to an enlarged scale as compared with Fig. 5, showing the skin held by an appliance which is—in turn—anchored to the frame.

Fig. 7 is an elevation, and Fig. 8 a plan of an appliance according to a further modification; and Fig. 9 is a fragmentary plan view.

In the several figures of the drawings, like characters of reference denote like or equivalent parts wherever they occur.

Referring first, more particularly, to the appliance illustrated in Figs. 1 to 3, inclusive, a body casting A of aluminium, or other suitable metal, includes an arm 1; a smooth flat table portion 2 which constitutes a relatively fixed jaw component; a pair of suitably spaced hook-like members or protuberances 3, arranged one behind another and projecting from portion 4 of the body A; and a finger ring 5.

Pivots associated with arms 1 of body A is a lever 6, 6^a whereon is provided a lateral pin 7 which extends through and is revoluble in a bearing boss or enlargement 8 formed on arm 1, the end of said pin 7 being riveted over a washer 9.

Arm 6 of said lever 6, 6^a forms a thumb piece, whilst arm 6^a is in the form of a cam or wedge on the operative face of which are formed transverse grooves or ridges as shown. Said arm 6^a constitutes the relatively movable component of a gripping device of which, as before stated, the table portion 2 provides the fixed component.

Said lever 6, 6^a tends to remain in the position illustrated in Figs. 1 and 2, i. e. with the jaw cam or wedge 6^a in contact with or near the jaw table 2 under the influence of a coiled wire spring 10 one end of which is attached to the jaw arm 6^a, whilst the other end is attached to a lateral lug 11 cast on arm 1. Jaw member 2 projects forwardly somewhat beyond jaw member 6^a for the purposes before described.

In the application of the appliance to a skin *s* to be strained or stretched and dried, the operator will insert a finger through said ring 5, and with his thumb push the lever arm 6 to cause jaw cam or wedge arm 6^a to retire and more or less open the gap 12, and this against the resistance of said spring 10: the appliance will now be fitted to an edge of the skin *s* so that a portion of the skin's edge enters said gap 12, and the thumb piece 6 will be released, with the result that, under the influence of spring 10, lever 6, 6^a will move about fulcrum pin 7 and the skin will be firmly held or gripped between the transversely ridged face of the cam or wedge jaw member 6^a and the smooth flat face of the jaw member 2. Then, one or other of the hook-like projections or protuberances 3 will be engaged or anchored by the operator in a selected or appropriate interstice or mesh opening of the mesh-work 13 of frame 14, as illustrated in Figs. 5 and 6. It is to be noted that as the pulling effect on the skin is increased the holding or gripping action of the jaw 6^a, 2 is intensified or enhanced.

By the employment of a plurality of hook-like members or protuberances or stops arranged one behind another, any given pitch of frame mesh may be divided or subdivided into several adjustment positions corresponding with the number of hook-like members or stops provided. Consequently, a frame of coarser mesh, and therefore lighter and of cheaper manufacture, may be used to obtain finer graduations of adjustment than would be possible with the use of an appliance having a single anchoring hook. For example, a mesh of one inch pitch may be divided into two half inch graduations by the use of two hooks or stops arranged one behind another, such hooks being of one half inch pitch.

After the straining and drying operation is completed the appliance may be readily detached from the frame and skin.

In the modification illustrated in Fig. 4, 65 the hook-like projections or protuberances 3

are cast on a tapering plate carrier 15 which is slideable in a tapered slot 16 with undercut walls formed in the underside 4 of body casting A. If, therefore, one or more of the hook-like projections 3 should become broken, or if hooks of other shape and/or of different pitch are required to be used, the carrier plate 15 may be removed and replaced by a new plate with hooks.

Referring now to Figs. 7 and 8 of the drawings, the appliance therein illustrated is, in effect, divided or separated into two portions which are so formed and connected or articulated together that additional or supplementary tension may be imposed on a skin, 20 when in situ on the frame, by simply turning a wing piece.

In this modification, a body casting A is provided with a shank extension 17 which is curved or recessed and terminates in a bearing boss 18 wherethrough a passage is formed. A second casting comprises a finger hold portion 5, two hook-like members or protuberances 3 arranged one behind another, and a shank extension 19 which is curved or recessed in opposite or reverse manner to the curvature of said first mentioned shank 17, and terminates in a similarly passaged bearing boss 20.

Said bosses 18, 20 are loosely disposed on pins 21 between a pair of plates 22, 23 on one of which is formed a wing piece 24.

In use, the appliance is connected to the edge of a portion of a skin *s* to be treated and is anchored to frame 14 in manner as hereinbefore described.

Should it be desired, however, to subject the skin to additional or supplementary tension or stress, said wing piece 24 is turned, with the result that said shank bosses 18, 20, 10¹ are carried into nesting engagement in the recessed shanks (the boss of one shank lying in the recess of the other shank, as illustrated in Fig. 9) so that the appliance, as a whole, is substantially shortened, and will 11⁰ positively remain in this contracted condition until said wing piece 24 is wilfully actuated again to restore the parts to their "elongated" positions.

It is to be noted that the arrangement of 11⁵ said hooks 3 is such that the appliance, when applied to frame 14, remains flat thereon, irrespective as to which of said hooks is then in engagement with meshwork 13.

What I claim as my invention and desire to secure by Letters Patent is:—

1. An appliance for use in the straining or stretching of skins on frames, which appliance embodies means whereby a portion of the edge of a skin may be detachably held or gripped; a plurality of hook-like members carried by said means, in combination with a screen, said hook-like members being spaced one behind another unequally with respect 13⁰

to the spacing of parallel strands of said screen.

2. An appliance for use in the straining or stretching of skins on frames, comprising a pair of oppositely curved shank portions, a member pivotally connected to the ends of said portions, a skin gripping device carried by one of said portions, and anchoring means carried by the other portion, the pivotally connected end of each portion being receivable in the curve of the other portion by operation of said member.

3. An appliance for use in the straining or stretching of skins on frames, comprising means whereby a portion of the edge of a skin may be detachably held, and a plurality of hook-like members spaced apart and arranged one behind another to permit of fine adjustment on such frames, the frame-engaging parts of said members being equidistant perpendicularly from said means so that said appliance, when applied to a frame, remains substantially flat thereon irrespective as to which of said hook-like members is then in engagement with the frame.

4. An appliance for use in the straining or stretching of skins on frames, comprising means whereby a portion of the edge of a skin may be detachably held, a plurality of hook-like members spaced apart and arranged one behind another to permit of fine adjustment on such frames, means for contracting the distance between the first named means and said members, the frame-engaging parts of said members being equidistant perpendicularly from said means so that said appliance, when applied to a frame, remains substantially flat thereon irrespective as to which of said hook-like members is then in engagement with the frame.

In testimony whereof I affix my signature.
EVAN GEORGE WILSON.
